UNITED STATES PATENT OFFICE.

THEODORE SYNSTEBY, OF HANSKA, MINNESOTA.

ROAD GRADER.

Application filed October 11, 1924. Serial No. 743,019.

To all whom it may concern:

Be it known that I, THEODORE SYNSTEBY, a citizen of the United States of America, and resident of Hanska, in the county of Brown and State of Minnesota, have invented certain new and useful Improvements in Road Graders, of which the following is a specification.

This invention relates to road working machinery, such as a grader and ditcher, and particularly to a device for preventing a road working machine from swaying sidewise or from being displaced sidewise while the scraper blade or the like is operating on a roadbed.

In types of road scrapers or graders where the blade is set diagonal with respect to the direction of travel of the road machine, the resistance encountered by the scraper or blade tends to force the machine laterally and when the road is slippery, a sidewise skidding action results.

It is an object of this invention to provide novel means for bracing the machine against the aforesaid action and prevent skidding or lateral displacement of the wheels of the machine when the device is in operation.

It is a further object of this invention to produce a device of the character indicated which may be utilized in connection with road working machines now in common use, or which may be installed on new machines as equipment for accomplishing the result stated.

It is a still further object of this invention to produce a grader of the character indicated which can be adjusted to increase or diminish the resistance it affords to the movement of the road working machine, according to the conditions of the road and the requirements in practice.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote correspond-

ing parts in the several views, and in which—

Figure 1 illustrates a plan view of a conventional type of road working machine showing a device embodying the invention applied thereto;

Figure 2 illustrates a view in side elevation thereof;

Figure 3 illustrates a sectional view of a roadbed showing the application of the invention thereto;

Figure 4 illustrates a detail view of a telescopic arm;

Figure 5 illustrates a longitudinal sectional view thereof;

Figure 6 illustrates a sectional view on the line 6—6 of Fig. 4;

Figure 7 illustrates a view in side elevation of a runner or blade; and

Figure 8 illustrates a modified form thereof.

A conventional type of road working machine is illustrated by the dotted lines in Figs. 1, 2 and 3, whereas that part of the illustration in said figures in full lines constitutes an attachment for performing the functions described.

In the present embodiment of the invention, a road working machine 10 is provided with a frame consisting of members 11 and 12 held in place by a brace 13, all of which are secured to the rear axle of the road working machine by suitable fastenings 14, and the structure just described is further held by braces 15. One of the braces 15 extends from the member 11 upwardly to a point on the machine, and the other brace 15 extends from the member 12 upwardly to a similar point on the other side of the machine. The frame just described adapts the machine in order that the members 16 and 17 forming an upright frame may be erected.

A plate 18 is anchored to the member 12 at its outer end, and the said plate preferably extends transversely of the machine toward the roadside or ditch. The plate has an aperture or eye 19 to receive the hook or lug 20 of a plate 21 which is attached to a sectional prop or brace intended to prevent

lateral movement of the grading machine, as will presently appear.

In order to adapt the device to roads of different widths, the prop or brace has sections telescopically arranged with relation to one another, and in order to produce a prop or brace of sufficient strength to withstand the strain incident to its use the said brace, in the present embodiment of the invention, comprises two side members 22 and 23 which are held in spaced relation to each other by plates 24, which plates may be located above and below the members 22 and 23, and two of the plates which align, one each at the top and bottom of the said members, have apertures 25 to receive a pin 26 by which the telescopic member 27 of the brace or prop is held at different positions of adjustment. The plates acting in conjunction with the side members 22 and 23 constitute guides for the telescopic member of the prop and serve to prevent displacement of the telescopic member with relation to the assembly. The telescopic member has a plurality of apertures 28, any one of which may receive the pin 26, and by this means, the lateral brace or prop may be increased or reduced in length in order that it may extend to proper position with relation to the side of the road, or the ditch thereof.

A shoe or runner is oscillatably mounted at the end of the brace, and to that end, plates 29 and 30 are secured to the telescopic member, and the said plates extend beyond the end of the telescopic member. Apertures such as 31 are formed at the ends of the plates to receive a pintle 32 on which the runner or shoe is oscillatably mounted, as will presently appear.

A plate 33 has an apertured boss or lug 34 which fits between the ends of the plates 29 and 30, and the pivot pin 32 extends through the aperture of the said boss or lug so that the plate may oscillate. A runner or shoe 35 is secured to the plate 33 by fastenings such as rivets or the like, and the said runner has an outwardly curved lower edge. An apertured quadrant 36 is secured to the runner or plate on which the runner is mounted, and the said quadrant is connected to a stationary part of the road grading machine, as, for instance, the scraper thereof, by a cable or link 37, and this serves to hold the runner at different positions of adjustment in order that its resistance may be increased or diminished, according to the requirements in practice; it being apparent that if the cable or link 37 is connected to the segment at the different holes, the angle of the runner to the line of draft of the machine may be regulated. The runner is in the nature of a sharp steel blade with a curved front end, and it has been found in practice that when the angle "B" has been at 84° and the angle "A" at 70°, and when

the telescopic brace or prop was adjusted as it is shown in Fig. 4 with a length of about 10 feet, the runner blade engaged and was partially imbedded in the ground at such an angle as to cause pressure and thrust in the direction 2, illustrated by the arrow on Fig. 1, a condition which counteracted the tendency of the grader to slide in the direction 1, shown by arrow on Fig. 1.

When the grader is to be moved without operating, the device for carrying the runner may be supported clear of the ground by suitable tackle attached to the top of the frame where it may be held by the means illustrated.

It is intended, of course, that the runner should engage the bank, side of the ditch, or deposit at the side of the roadway, and the structure which it engages at the side of the roadbed would vary in different localities, and hence the term "deposit" is employed herein as engaged by the runner. The term "deposit" is intended to include any formation at the side of the road which can be engaged by the runner and which will constitute an abutment or resistance to the movement of the runner in a direction transversely of that in which the road machine is traveling.

In Fig. 8 there is shown a modified form of plate A which is reversible.

I claim:

1. In a road working machine having a laterally extending brace, a member on the outer end of the brace for engaging deposits at the side of the road for obviating movement of the machine transversely, and means for adjusting the said member to an angle with relation to the direction of movement of the said machine.

2. In a road working machine, a brace comprising telescopically arranged members having means for securing the members at different positions of adjustment, means for connecting the brace to the machine, and a runner on the outer end of one of the telescopic members for engaging deposits at the side of a road.

3. In a road working machine, a beam-like element comprising telescopically assembled elements having means for securing the said elements at different positions of adjustment, means for pivotally connecting the beam-like element to the machine whereby it extends transversely of the machine, a runner secured to the outer end of one of the telescopic members, and means for suspending the outer end of the beam-like member when the machine is inoperative.

4. In a road working machine, a brace comprising telescopically arranged members having means for securing the member at different positions of adjustment, means for connecting the brace to the machine, a runner on the outer end of one of the telescopic

members for engaging deposits at the side of a road, means for pivotally connecting the runner to one of the telescopic members of the brace whereby the said runner may oscillate laterally, and means for holding the runner at different positions of adjustment laterally.

5. In a road working machine, a brace comprising telescopically arranged members having means for securing the members at different positions of adjustment, means for

connecting the brace to the machine, a runner on the outer end of one of the telescopic members for engaging deposits at the side of a road, an apertured quadrant carried by ¹⁵ the runner, and a brace adapted to be connected to the quadrant in any of the apertures and to a stationary part of the machine for holding the runner at different positions of lateral adjustment.

THEODORE SYNSTEBY.
